Joseph M. Ward.

UNITED STATES PATENT OFFICE.

JOHN W. AKERMAN, OF NEWBURYPORT, MASSACHUSETTS.

INTERNAL-COMBUSTION ENGINE.

974,544.

Specification of Letters Patent.

Patented Nov. 1, 1910.

Application filed January 17, 1910. Serial No. 538,367.

To all whom it may concern:

Be it known that I, JOHN W. AKERMAN, a citizen of the United States, and resident of Newburyport, county of Essex, State of Massachusetts, have invented an Improvement in Internal-Combustion Engines, of which the following description, in connection with the accompanying drawing, is a specification, like characters on the drawing representing like parts.

This invention relates to that type of engines in which the combustion of a charge of explosive gas in the cylinder is utilized to effect the reciprocation of the piston and the rotation of the connected crank-shaft, the charge being introduced under pressure to the cylinder.

My present invention has for its object the production of a two-cylinder internal-combustion engine of the two-cycle type, the cylinders being opposed and the pistons being so connected with the crank-shaft as to move in unison in the same direction.

In the present embodiment of my invention the two cylinders are rigidly connected by a two-part base which also constitutes the crank-case, the base being divided into two separate chambers by a disk revolving with the shaft, each chamber communicating with one of the cylinders in such manner that on the outward, or compression, stroke of its piston, a fresh charge of gas is drawn into the chamber while a previous charge is being compressed in the cylinder ahead of the piston. On the return or working stroke, effected by the combustion of such compressed charge, the fresh charge previously drawn into the chamber in the base is compressed and forced into the cylinder behind the piston, while the burnt gases are driven out of the cylinder through the exhaust port.

As will appear hereinafter one piston is making its working stroke while the other piston is compressing the charge in its cylinder preliminary to ignition and at the same time it is drawing into the corresponding chamber in the base the supply of gas for the next charge. Every alternate stroke of each piston is a working stroke, due to the explosion of a charge, and herein I have shown the working stroke as inward while the compression stroke for the charge in the cylinder is outward for each piston. Thus there is a separate impulse or explosion for each half-revolution of the crank-shaft.

The various novel features of my invent-

tion will be fully described in the subjoined specification and particularly pointed out in the following claims.

Figure 1 is a partial side elevation and vertical longitudinal section of an internal-combustion engine embodying one form of my present invention; Fig. 2 is a horizontal sectional view thereof taken through the center of the crank-shaft; the latter, with the pistons and piston-rods, being shown in elevation; Fig. 3 is a transverse section on the line 3—3, Fig. 2, taken through the inner end of the left-hand cylinder and looking toward the right, showing the two-part base; Fig. 4 is a view in elevation of the right-hand member of the two-part base, looking directly at Fig. 3; Fig. 5 is a central horizontal section of the base member, detached; Fig. 6 on a smaller scale is an inner side view of one of the base members.

Herein I have illustrated only so much of the engine and its appurtenances as will be necessary to a proper understanding of my invention.

Referring to Fig. 2 the crank-shaft 1, having an attached fly-wheel 2, is provided with a single crank 3, see dotted lines Figs. 1 and 2, connected by counter-balancing cheek-pieces 4 with the two parts of the shaft, the crank having rigidly secured to or forming a part of it a disk 5 concentric with the shaft and shown herein as midway between the cheek-pieces 4. The shaft has bearings in aligned hubs 6 oppositely extended from the opposite sides of the members of the two-part base, each of said members comprising an internally cylindrical body 7 closed at its outer side and having an annular seat 8 at its inner, open side, the two open sides being abutted with the seats in register, as shown in Fig. 2, to receive snugly the periphery of the disk 5, thereby enabling said disk to divide the base into two separate chambers B, B', Fig. 2. A series of transverse bolts 9 rigidly connect the base members, as best shown in Fig. 1.

The exterior of the body 7 of each base member presents opposite and parallel flat end faces 10, 11, so arranged that when the members of the base are bolted together the end face 10 of one member will be adjacent and in the plane of the end face 11 of the other member, each face 11 having an extension at one side formed by the lateral flange 12. As shown in Fig. 2 the flanges project from opposite sides of the base, and

the end faces 11 are each provided with a large elongated opening 13 for the reception of the piston rods and also serving to establish continuous communication with the inner ends of the cylinders, as will be referred to hereinafter. Each body 7 has formed in it a passage 14 above the opening 13, and one of said passages communicates with the chamber B while the other passage 15 communicates with the chamber B' in the base, said passages being shown in full and dotted lines in Fig. 1, and it will be seen therefrom that they extend in opposite directions.

15 The base constitutes a crank-case, as will be evident, the cheek-pieces 4 bearing against the opposite sides of the base and preventing any longitudinal movement of the shaft, while the disk 5 divides the base 20 into the two separate chambers, yet said disk revolves with the shaft and has its bearings in the two-part annular seat 8.

The two cylinders C and C' are alike and hence only one need be described in detail. 25 Each cylinder is open at its inner end and is provided with a lateral flange 15 which abuts against the adjacent end faces 10 and 11 of the base members, suitable bolts 16, clearly shown in Fig. 3, rigidly securing the 30 cylinder flanges to the base. As shown two of the bolts 16 connect the cylinder flange with a base flange 12, holes 12* being provided in the latter for said bolts, while the other two bolts 16 enter the adjacent end 35 face 10 of the other base member. The cylinder casting has a by-pass 17 formed in it, registering at one end with one of the passages 14, while the other end of said by-pass opens into the cylinder and forms the inlet 40 port 18, see Fig. 1, said ports being opened and closed by the moving pistons, each inlet port being fully open when the piston is at the extreme end of its inward stroke. I have shown the outer end of each cylinder as 45 jacketed at 19, for cooling purposes, the explosion of the charge taking place in the outer, closed end of the cylinder. Exhaust ports 20 are formed in the cylinders opposite the inlet ports, but of somewhat larger 50 area, and so arranged that the moving piston opens the exhaust ports before opening the ports 18 and closes the latter before completely closing the exhaust ports.

Piston control of the ports is not of itself 55 broadly new, but I have herein adopted such control as it is simple and positive, and obviates the use of valve mechanism. Intake ports 21 are made in the cylinders, externally connected by suitable piping 22, Fig. 60 2, communicating with the source of supply, not shown, of the explosive gas, said ports being located near the inner, open ends of the cylinders and so arranged as to be completely uncovered when the pistons are at 65 the extreme outer ends of their strokes.

Said intake ports are closed on the inward or working stroke at such a time as will permit a sufficient quantity of the gas to have been drawn into the cylinder for the next charge. The cylindrical, hollow pistons D, D' are connected by piston-rods E, E' with the crank 3 at opposite sides of the disk 5, see Fig. 2, the two piston rods working in the openings 13 of the two members of the base, and from an inspection of Figs. 75 1 and 2, it will be evident that the two pistons move in unison in the same direction, so that the compression stroke of one corresponds with the working stroke of the other, and vice versa. On the outer end of each 80 piston I provide a transverse baffle 23 curved upward toward the inlet ports 18, so that when a fresh charge is admitted to a cylinder the baffle is interposed between the opposite inlet and exhaust ports, as 85 shown at the left, Fig. 1. This prevents the incoming fresh charge from driving directly across the piston head to the exhaust port, and gives the fresh charge a better opportunity to drive out the burnt gases of 90 the previously exploded charge.

The charge is exploded in the outer end of each cylinder by means of an igniter of any suitable character, indicated at F and F', Fig. 1, and operated in usual manner, forming no part of my invention.

It will now be understood that chamber B is always in communication with the inner end of cylinder C through the corresponding opening 13, and by means of the passage 100 14 and by-pass 17 said chamber communicates with the outer end of the cylinder C when the inlet port 18 therein is opened. Similarly, chamber B' and the inner end of cylinder C' are always in communication, 105 and intermittently said chamber and the outer end of the cylinder C' communicate through the corresponding passage 14 and by-pass 17. As shown in Figs. 2 and 3 the longitudinal centers of the two cylinders are 110 laterally offset, to provide for the side by side connection of the piston-rods with the crank 3, and practically I have two opposed engines each working alternately to rotate the crank-shaft, imparting substantially 115 continuous power thereto.

In operation the outward stroke of a piston creates a partial vacuum in the connected chamber (B or B') of the base, and near the end of such stroke the intake port 120 21 is uncovered, a charge of the explosive medium rushing into the chamber from the source of supply. As the crank passes dead-center the previous charge is exploded and the piston is driven inward, closing intake 125 port 21 and compressing the charge in the base chamber, forcing it through the passage 14 and by-pass 17, and into the outer end of the cylinder when the inlet port 18 is 130 uncovered by the piston near the end of its

inward stroke. The completion of the stroke causes the proper charge to be forced into the outer end of the cylinder, and as the exhaust port 20 is uncovered before the inlet port 18 is opened, and remains open until said port 18 is again closed, the incoming charge clears the cylinder of the burnt gases therein. On the outward stroke the piston compresses the fresh charge in the explosion end of the cylinder while it is drawing a new supply of the explosive medium into the base chamber, previously described. Thus while each piston is compressing the charge next to be exploded it is drawing into the base chamber a fresh supply of explosive medium, and this supply is compressed by the piston on its inward, working stroke, due to the explosion of the compressed charge.

20 Inasmuch as the two pistons perform their various functions in alternation, and operate alike, the above description of the operation of one half of the engine is sufficient for a proper understanding of the invention.

25 A high compression in the base is provided for in my invention, the construction of the engine is simple, strong and durable, and the engine is smooth running and powerful. By introducing a suitable lubricant to the base the crank, piston-rod connections, shaft-bearings, and the pistons can be easily lubricated, the rotation of the crank throwing the lubricant in all directions upon every moving part. The disk as it revolves in the annular seat 8 serves not only as a separator between the chambers B and 'B' but it also supports the crank between the two piston rods connected therewith.

30 40 Various changes or modifications may be made by those skilled in the art without departing from the spirit and scope of my invention as set forth in the claims annexed hereto.

45 Having fully described my invention, what I claim as new and desire to secure by Letters Patent is:—

1. The combination, with two opposed stationary cylinders, each cylinder having oppositely located inlet and exhaust ports near the outer end of the piston-stroke, and an intake port near the inner end of the piston stroke and connected with a source of supply, a rotatable shaft between the cylinders and having a single crank, pistons in the cylinders, operatively connected with the crank, and a chambered base connecting the inner ends of the cylinders and communicating with the cylinders at their inner ends, 50 of a solid revolving disk fixed on the crank between the connections intermediate said crank and pistons and dividing the base into two permanently separated chambers, one for each cylinder, a passage connecting each chamber with the inlet port of its cyl-

inder, and means to ignite the explosive charge when admitted to and compressed in the outer end of a cylinder, each piston in its reciprocation opening and closing the intake, inlet, and exhaust ports of its cylinder.

2. The combination, with two opposed and stationary cylinders, a chambered base connecting their inner ends, a rotatable shaft supported by said base and having a single crank, and pistons in the cylinders, operatively connected with the crank, of a solid disk concentric with the shaft and fixed on the crank, dividing said base into two permanently and completely separated chambers each communicating continuously with the inner end of one of the cylinders, and means governed by the pistons to draw a fresh supply of explosive medium into a chamber on the outward stroke of the piston in the communicating cylinder and to force it into the outer end of such cylinder on the next inward stroke.

3. The combination, with two opposed and stationary cylinders closed at their outer ends and open at their inner ends, a connecting base having two permanently separated chambers, each communicating continuously with the inner end of a cylinder, a piston in each cylinder, and means governed by the pistons to establish temporary communication between a chamber and the outer end of its cylinder on the inward stroke of the piston therein, of a rotatable shaft having a single crank operatively connected with the pistons, separate ports in the cylinders near their inner ends and communicating with a supply of explosive medium to introduce a charge to said chambers, in alternation, on the outward strokes of their corresponding pistons, and means fixed on the single crank to maintain the permanent separation of the chambers in the base.

4. The combination, with a base having an internal annular seat, a shaft rotatably mounted in the sides of said base and having a single crank, a solid disk fixed on said crank and revolving in the seat, to divide the base into two permanently separate chambers, a stationary cylinder in continuous communication with each chamber, and pistons in the cylinders, operatively connected with the single crank at opposite sides of the disk, of a by-pass leading from each chamber and terminating in an inlet port opening into the corresponding cylinder near its outer end, said port being closed by the piston on the outward stroke thereof and opened on the inward stroke.

5. In an internal-combustion engine, a two-part base having alined bearings in the opposite sides thereof and an intermediate, internal annular seat at the abutting faces of the two parts of the base, a shaft rota-

2
tablly mounted in said bearings and having a single crank within the base, and a solid revovlble disk fixed on said crank and hav-
ing its periphery fitting snugly in said seat,
5 to divide the base into two permanently separated chambers, combined with two op-
posed cylinders attached to the ends of said base and each communicating continuously at its inner end with a chamber, pistons in
10 the cylinders, operatively connected with the crank at opposite sides of the disk, and

means governed by the pistons to intermit-
tingly connect each chamber with the outer end of its cylinder.

In testimony whereof, I have signed my ¹⁵ name to this specification, in the presence of two subscribing witnesses.

JOHN W. AKERMAN.
